YORK.

ELECTRICAL APPLIANCE.

1,227,241.

Specification of Letters Patent. Patented May 22, 1917.

Application filed August 7, 1914. Serial No. 855,546.

To all whom it may concern:

Be it known that we, CARL H. BISSELL and ELDA G. SMITH, citizens of the United States, and residents of Syracuse, in the county of Onondaga and State of New York, have invented a certain new and useful Electrical Appliance, of which the following is a specification.

This invention has for its object an electrical appliance, particularly adapted for storage battery charging stations in railroad terminals and coach yards; and it consists in the novel combinations and constructions hereinafter set forth and claimed.

In describing this invention, reference is had to the accompanying drawings, in which like characters designate corresponding parts in all the views.

Figures 1 and 2 are sectional views, partly in elevation, of this appliance, an extension base being shown in Fig. 1, and omitted in Fig. 2.

Fig. 3 is a plan view of the appliance, the upper section of the housing being removed.

This appliance comprises a receptacle, a support therefor, and a housing including an upper section and two lower sections or bases upon which the support for the receptacle and the upper section of the housing are interchangeably mounted, one of the lower sections having a cap piece associated therewith, which is interchangeably mountable with the upper section on the other base section of the housing.

1 and 2 are receptacles or sockets mounted upon a support, as a plate 3, diagonally opposite each other and with their entrances facing laterally in opposite directions, each socket having binding devices 4, 5 at their rear ends for connection to electric wires, the binding devices being mounted on the terminal pieces 6, 7 of the sockets and the binding devices of each socket being located at the side of the other socket.

As here shown, the plate 3 is square and the rear ends of the receptacles or sockets overlap each other as seen in Fig. 3. The plate 3 is also formed with suitable insulated wire openings 8 located in the rear of the receptacles 1, 2 nearly beneath the binding devices, the wire openings communicating with the base or lower section of the housing upon which the plate 3 is mounted. Each recep-

tacle is connected to the plate 3 in any suitable manner, as by screw bolts 9.

10 is the main base or lower section of the housing, and 11 is a supplemental or extension base or lower section upon which the plate 3 may be interchangeably mounted. 12 is the upper section of the housing which is interchangeably mountable upon either the bases 10 or 11.

The main base 10 is a conduit outlet box having internally threaded nipples 13 for connection with electrical conduits, an opening 14 at its upper side, an upwardly extending flange 15 skirted the opening, and a bearing face 16 around the flange. The extension base or lower section of the housing is carried at the upper end of a pipe or conduit 17, the lower end of which is connected to a cap piece 18 interchangeably mountable with the upper section 12 of the housing on the open side of the base 10. The pipe 17 screws at its opposite ends into internally threaded nipples 19, 20 provided on the base 11 and cap 18.

The extension base 11 is formed with an opening 14^a skirted by a flange 15^a, which flange is surrounded by a bearing face 16^a, all similar to the opening, flange and bearing face 14, 15, 16 of the main base 10. The plate or support 3 may be secured to either of the bases 10, 11 by screws 21 extending through openings in the plate 3 and threaded into lugs 21^a or 21^b in the base 10 or 11, the plate 3 resting upon the edge of the flange 15 or 15^a.

The upper section of the housing which is interchangeably mountable upon either of the bases 10, 11, is formed with a flange 22 complementary to the bearing face 16 or 16^a and is attachable to either of said bases by screws 23 extending through threaded openings in the flange and in the bearing face 16, a gasket 24 being usually interposed between the flange and the bearing face. The cap piece 18 is also formed with a bearing face 25 complementary to the bearing face 16.

The section 12 of the housing is formed with a wall 26 which skirts the sides of the receptacles 1, 2 and which is provided with the flange 22 at its lower margin, this wall 26 having openings 27 aligned with the entrances of the receptacles or sockets 1, 2.

28 are spring pressed hinged covers for

the openings 27, said covers being hinged to leaves 29 projecting upwardly from the wall 26 and top of the section 12, the hinge leaves 29 being shaped to house the springs 30 surrounding the hinge pins.

31 is a plug movable into either one of the sockets 1, 2, and 32 are eyebolts hinged to the section 12 and movable into open-ended slots or notches 33 provided in lugs 10 34 on opposite sides of each plug 31; and 35 are wing nuts screwing on the eyebolts against the lugs 34 for holding the plug 31 from withdrawal. The eyebolts are mounted on pins 36 which are supported by lugs 15 37, 38 projecting from the wall 26 of the housing section 12.

In use, the appliance is mounted at one side of a car track or between double tracks, as will be understood by those skilled in the 20 art, and a plug 31 is attached to one end of a wire cord, the other end of which is attached to a plug which fits a socket on the car, which socket is connected to the storage battery.

25 This invention is particularly advantageous in that owing to the arrangement of the receptacles or sockets 1, 2, and other wire connections, a particularly compact appliance is provided.

30 What we claim is:

1. An electrical appliance comprising a support, and electrical receptacles mounted on the support diagonally opposite each other, each receptacle having binding devices located at one side of the other receptacle, substantially as and for the purpose described.

2. An electrical appliance comprising a support, and electrical receptacles mounted 40 on the support diagonally opposite each other and facing in opposite directions, each receptacle having binding devices located at its rear end and at one side of the other receptacle, substantially as and for the purpose 45 specified.

3. An electrical appliance comprising a support, and electrical receptacles mounted on the support diagonally opposite each other, each receptacle having binding devices located at one side of the other receptacle, the support being formed with wire 50 holes located at the rear of each receptacle and at the side of the other receptacle, substantially as and for the purpose set forth.

55 4. An electrical appliance comprising a support, and electrical sockets mounted on the support diagonally opposite each other and facing laterally in opposite directions, each socket having a binding device located 60 at its rear end and arranged at one side of the other socket, the base being formed with

wire openings in the rear of each socket, substantially as and for the purpose described.

5. An electrical appliance comprising a support in the form of a plate, receptacles mounted on the plate diagonally opposite each other and facing laterally in opposite directions, the receptacles having binding devices at their rear ends, the binding devices of each receptacle being located at the side of the other receptacle, and a housing 70 inclosing the receptacles and including a section having entrance openings aligned with the front ends of the receptacles, substantially as and for the purpose specified.

6. An electrical appliance comprising a base, receptacles mounted on the base and having entrance openings facing laterally, and a housing including upper and lower 80 sections, the upper section having side walls skirting the receptacles and formed with openings in its lateral side aligned with the entrances of the receptacles, substantially as and for the purpose set forth.

85 7. An electrical appliance comprising a base, receptacles mounted on the base diagonally opposite each other and facing in opposite directions, and a housing including upper and lower sections, the upper section 90 being mounted on the lower and including a side wall skirting the receptacles, opposite sides of said wall being formed with openings aligned with the entrances of the receptacles, the lower section of the housing being provided with means for connection with an electrical conduit, substantially as and for the purpose described.

95 8. An electrical appliance comprising a support in the form of a plate, electrical 100 receptacles mounted on the plate diagonally opposite each other and facing laterally in opposite directions, the receptacles having binding devices at their rear ends, the binding devices of each receptacle being located 105 at one side of the other receptacle and the plate being formed with wire holes in the rear of each receptacle and at one side of the other receptacle, and a housing inclosing the receptacles and having entrance 110 openings aligned with the front ends of the receptacles, substantially as and for the purpose specified.

In testimony whereof, we have hereunto signed our names in the presence of two 115 attesting witnesses, at Syracuse, N. Y., this 25th day of May, 1914.

CARL H. BISSELL.
ELDA G. SMITH.
